(57) **CLAIM**

The ornamental design for a bowling ball carrier, as shown and described.

DESCRIPTION

FIG. 1 is a front and top perspective view of a bowling ball carrier of the present invention;

FIG. 2 is a top plan view of the carrier shown in FIG. 1, in which the interior of the front pouch is shown;

FIG. 3 is a front elevation view of the carrier shown in FIG. 1;

FIG. 4 is a bottom plan view of the carrier shown in FIG. 1, in which the exterior of the front pouch is shown;

FIG. 5 is a left side plan view of the carrier shown in FIG. 1;

FIG. 6 is a rear elevation view of the carrier shown in FIG. 1;

FIG. 7 is a front and top perspective view of the carrier shown in FIG. 1, with a bowling ball, shown in dotted lines for illustrative purposes only and not forming a part of the claimed design, secured in the pouch; and,

FIG. 8 is a top plan view of the carrier shown in FIG. 7, with the bowling ball in broken line form for illustrative purposes only.
